DESIGN FOR A MONOPLANE

Paul H. Kemmer and Carl E. Reichert,
Dayton, Ohio

Application February 25, 1939, Serial No. 83,209

Term of patent 7 years

To all whom it may concern:

Be it known that we, Paul H. Kemmer and Carl E. Reichert, citizens of the United States residing at Dayton, in the county of Montgomery and State of Ohio, have invented a new, original, and ornamental Design for a Monoplane, of which the following is a specification, reference being had to the accompanying drawings, forming part thereof.

Figure 1 is a top plan view of a monoplane, showing our new design;

Figure 2 is a front view of the said monoplane;

Figure 3 is a side view thereof, and
Figure 4 is a perspective view.

We claim:

The ornamental design for a monoplane, as shown.

PAUL H. KEMMER.
